UNITED STATES PATENT OFFICE

138,137

DESIGN FOR A PICKLE FORK

John F. Brown, Los Angeles, Calif.

Application April 19, 1944, Serial No. 113,311

Term of patent 14 years

(Cl. D54—12)

To all whom it may concern:

Be it known, that I, John F. Brown, a citizen of the United States and residing at Los Angeles, in the county of Los Angeles, State of California, have invented a new, original, and ornamental Design for a Pickle Fork, of which the following is a specification, reference being had to the accompanying drawing, forming part thereof, in which:

Fig. 1 is a perspective view of a pickle fork showing my new design;

Fig. 2 is an end elevation thereof looking at the end carrying the tines;

Fig. 3 is a perspective view thereof with the fork in reverse position compared to Fig. 1, and

Fig. 4 is an end elevation thereof looking at the handle end of the fork.

I claim:

The ornamental design for a pickle fork, as shown.

JOHN F. BROWN.
